UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,312,161.

Specification of Letters Patent.

Patented Aug. 5, 1919.

Application filed May 24, 1918. Serial No. 236,298.

To all whom it may concern:

Be it known that I, CORNELIUS B. CORCORAN, a citizen of the United States, residing in borough of the Bronx, in the county 5 of the Bronx, city and State of New York, have invented certain new and useful Improvements in Type-Writing Machines, of which the following is a specification.

My invention relates to devices for guiding cards, envelopes, and the like around the cylindrical platens of typewriting machines. The object of the invention is to increase the adaptability and usefulness of such devices, and also to improve the scales which are 15 mounted upon the machine frame at the front of the platen on opposite sides of the printing point.

My invention is in the nature of a combined card guide and platen scale; the card 20 guide comprising two fingers, one extending up across the printing line at each side of the printing point, and each pivotally mounted at its lower end for swinging down to horizontal or cumbent position.

According to my improvements, when the card guide is swung down, its horizontal 25 edge may coincide with the printing line on the platen, and letter-space graduations are provided along said edge, to be used like the ordinary wing scales on the Underwood typewriting machine. When the card guides are swung up to working positions, these 30 graduations are no longer available as letter-space indications, but I attach to or form upon each of the card guides an arm extending at right angles thereto, the upper edge 35 of such arm being swung to horizontal position when the card guide is swung to vertical position, and the upper edge of said arm then coinciding with the printing line, and being also provided with letter-space graduations, so that whether the card guide is 40 down or up, there is a scale available.

These combined card guides and scales are 45 shown mounted upon a support which is shiftable up and down with the platen, although this shiftable feature is not necessary in all cases.

Viewed in one way, it will be noted that 50 a single scale structure is provided for use both when writing upon an ordinary sheet of paper, and when writing upon cards, heavy envelopes, etc., the scale including or comprising scale members or wing scales

supported by a suitable supporting member 55 and movable into different positions; in one of which they are designed for use in typing upon an ordinary sheet of paper while in the other position the scale members or wing scales are designed for use when cards or 60 heavy envelopes are to be typed; a plurality of such scale members being ordinarily employed, although a single wing scale may be used if desired.

I aim to produce a device which will be 65 simple in construction and capable of ready adjustment as above explained.

The accompanying drawing illustrates the preferred embodiment of my invention; although it will be appreciated that the same 70 may be embodied in other specific forms.

Other features and advantages will hereinafter appear.

In the accompanying drawings, Figure 1 is a fragmentary view in perspective illustrating my improved platen scale, together with so much of a typewriter as is necessary in order to show its connection therewith and method of operation.

Fig. 2 is a similar fragmentary view showing my invention in elevation, and as seen from a position at the front of the machine equipped therewith.

Fig. 3 is a similar fragmentary view upon a plane extending at right angles to the axis 85 of the platen.

The reference numeral 4 designates a platen supported in a carriage, the usual means being provided for advancing it in a series of step-by-step movements.

The platen 4 in the Underwood typewriting machine is shiftable vertically into upper and lower-case positions, movement being communicated to the platen by shift keys 5 acting through bell crank levers 6 pivoted at 7, and carrying a shifting-bar 8; motion being communicated from the bar to the platen to move it vertically, as usual.

The reference numeral 9 designates a vertically shiftable scale supporting member to which motion is communicated from the platen shifting-bar 8 through an arm 10 in the embodiment of my invention illustrated. Inasmuch, however, as this present invention is not concerned with the mechanism for moving the supporting member vertically, such mechanism is not illustrated in detail and will not be described at length.

herein. Attention is called to the same mechanism disclosed in Patent No. 1,920,647, issued March 27, 1917, to Alfred G. F. Kurovski. In some machines, it will be unnecessary to shift my improved device at the case-shifting operation.

The supporting member 9 is illustrated as provided with two arms 11 spaced apart, one at each side of the printing point, and the upper ends of these arms stand adjacent the platen and the line of writing, as shown in Fig. 1. The reference numerals 12 designate two wing scales pivotally secured at 13, one at the free upper end of each of the vertically extending arms of the supporting member 9. It will therefore be appreciated that the scales in question are movably supported, that they may be swung upon their pivotal supports into different positions, and that they lie adjacent the platen and the line of writing, and that they may also, if desired, shift up and down with the platen.

It will be appreciated that the number of individual wing scales is of secondary importance, and that in accordance with my invention, considered in its broad aspect, a machine may be equipped with one or a plurality of my improved individual scales.

30 The devices 12 each comprise a scale arm 14 and a card-guide arm 15 disposed at right angles to each other, and extending from the pivotal points 13 at which the devices are connected with the arms 11 of the supporting member. Both arms are provided with the usual graduations, and are shown in their extreme positions in Figs. 1 and 2. When in the position in which they are illustrated in Fig. 1, the card-guiding arms 15 extend vertically, and act as card-guides or fingers to assist in holding a stiff card, envelop, or other article being written upon in proper contact with the platen 4. In this position the graduations shown on the horizontally extending arms 14 are available for the usual purpose of a scale, and, like the other arms, are supported substantially throughout their length by the broad top of the arms or supports 11 when horizontal. Fig. 2 shows the wing scales in the position which they may occupy when writing is being done upon an ordinary sheet of paper; the arms 14 being then swung into their lowermost position 55 below the line of writing, while the arms 15 assume a horizontal position, and the graduations at their upper ends then form an ordinary platen scale.

Means are preferably provided for locking the wing scales in the two extreme positions in which they are illustrated in Figs. 1 and 2, respectively, said means being illustrated as comprising depressions 16 formed in the material of the supporting members 60 or arms 11, and into which projections car-

ried by the arms 14 snap at the ends of the extreme movements of the said wing scales 12 about their pivotal connections 13. Locking means, if used, may be of any desired form.

Variations may be resorted to within the scope of the invention, and portions of the improvements may be used without others.

Having thus described my invention, I

1. In a platen scale for typewriters, a supporting member, the free end of which lies adjacent the line of writing; and a wing scale located adjacent and pivotally secured to the free end of said supporting member, and having a plurality of graduated portions extending at an angle to one another.

2. In a platen scale for typewriters, a supporting member the free end of which lies adjacent the line of writing; and a wing scale located adjacent and pivotally secured to the free end of said supporting member, and having an arm adapted to extend vertically to hold a card, said arm adapted to be swung down to horizontal position at the printing line and detained there, and comprising a scale adapted to indicate letter-spaces when in horizontal position.

3. In a platen scale for typewriters, a shiftable supporting member the free end of which lies adjacent and below the line of writing; and a wing scale located adjacent the free end of and pivotally connected with said supporting member, and having two arms extending at right angles to one another, one of said arms normally lying horizontally, and comprising a scale adapted to indicate letter-spaces, but adapted to be swung up on the pivot to hold a card, and when so swung up to carry the other arm to the writing line, said other arm comprising a scale adapted to indicate letter-spaces when so swung up.

4. In a platen scale for typewriters, a vertically shiftable supporting member the upper free end of which lies adjacent the line of writing; a wing scale pivotally connected with the free upper end of said supporting member and lying on the face adjacent the platen, and having two arms extending at right angles to one another; and means for locking said scale in two extreme positions, each arm comprising a scale, so that one arm normally serves to indicate letter-spaces, and when swung on the pivot serves as a card-holder, and when so swung brings the other arm to position adjacent the printing line, so that said other arm then indicates letter-spaces.

5. In a platen scale for typewriters, two supporting members spaced apart from one another and the free ends of which members lie adjacent the line of writing; and a wing scale pivoted upon the inner face of each member, toward the edge nearest

the other member, an arm of each wing scale normally lying across the top of its member and supported thereby throughout most of its length, and a second arm of each wing scale normally lying out of the way along its member, and comprising a scale to indicate letter-spaces, so that the first arm may be swung up to serve as a card-holder, and then the second arm indicates 10 letter-spaces.

6. In a platen scale for typewriters, two shiftable supporting members spaced apart from one another and movable in unison, and the free ends of which members lie adjacent the line of writing; and a wing scale pivoted upon each member having an arm adapted to extend vertically to hold a card, said arms being adapted to be separately swung down to horizontal position at the 15 printing line and detained there; and com-

prising a scale adapted to indicate letter-spaces when in horizontal position.

7. In a platen scale for typewriters, a vertically shiftable supporting member having two arms spaced apart from one another 25 and terminating adjacent the line of writing; two wing scales pivotally connected one with the free end of each of said arms, and each of which scales comprises two arms extending from the pivotal connection 30 aforesaid and at right angles to one another; and means for locking said scales in two extreme positions in each of which said arms extend parallel with and at right angles to the line of writing.
